LASTING MACHINE

George Goddu, deceased, late of Winchester, Mass., by Isabelle W. Goddu, executrix, Winchester, Mass., assignor to United Shoe Machinery Corporation, Paterson, N. J., a corporation of New Jersey

Application October 30, 1933, Serial No. 695,832

22 Claims.

(Cl. 12—2)

This invention relates to lasting machines, and more particularly to machines of that type that pull an upper by means of a gripper successively in different locations along the edge of the shoe bottom and fasten the upper after each upper-pulling operation. The invention is herein illustrated as applied to a machine the general organization of which is substantially as disclosed in Letters Patent No. 1,796,451, granted on March 17, 1931 upon an application of George Goddu, the machine having means for driving staples to fasten the upper to a lip on an insole or sole (hereinafter referred to generically as the sole) and means for clinching the staples on the lip. It is to be understood, however, that the invention is not limited to an organization of that particular character, nor to machines that fasten the upper to a lip; and it is also to be understood that it is not limited to machines that drive staples or other fastenings, but is applicable, for example, to machines in which the fastening means simply presses the marginal portion of the upper into position to adhere to the sole without the insertion of any fastening. Machines of the character illustrated in the above-mentioned Letters Patent are now commonly so constructed that the gripper operates on the upper in a location spaced somewhat lengthwise of the edge of the shoe bottom from the location where the upper-fastening means operates on the shoe; i. e., in a location at the left of that where the fastening is inserted, considered with reference to the operator's working position in front of the machine. It is therefore necessary that the operator move the shoe from left to right in the progressive lasting of each of its opposite sides, so that the lasting operation progresses toward the toe end of the shoe along one side of the shoe and toward the heel end along the other side. The present invention provides a construction such that if conditions should render it desirable both sides of a shoe may be lasted progressively toward the same end thereof; for example, toward the heel end. For this purpose the gripper, in the embodiment of the invention herein illustrated, is so mounted and controlled that it is shiftable at the will of the operator to carry the upper-engaging portions of its jaws lengthwise of the edge of the shoe bottom past the location of fastening insertion and thus to position the jaws for operation on the upper at either side of that location selectively. This permits the shoe to be moved in opposite directions in lasting its opposite sides respectively, so that the lasting may begin, for example, near the toe end and may progress

toward the heel end at each side. Novel mechanism is provided to enable the operator to shift the gripper quickly from one operating position to the other; and there are further provided novel means for maintaining the gripper in each operating position and for insuring against such damage to the machine as might result from its accidental displacement from either position.

The above and other features of the invention, including various novel details of construction and combinations of parts, will now be more particularly described by reference to the accompanying drawings and pointed out in the claims.

In the drawings,

Fig. 1 is a view substantially in right-hand side elevation of a portion of a machine in which the invention is embodied;

Fig. 2 shows partly in front elevation and partly in section the mechanism provided for shifting and controlling the gripper;

Fig. 3 shows the same mechanism as Fig. 2, partly in right-hand side elevation and partly in section;

Fig. 4 is a vertical section showing a portion of the means provided for insuring the proper positioning of the gripper when the machine is operating;

Fig. 5 is a perspective view showing more clearly than Fig. 1 how the gripper is mounted for swinging movements;

Figs. 6 and 7 illustrate the positions of the gripper jaws in relation to the fastening-inserting and clinching means in operating respectively at the opposite sides of a shoe; and

Fig. 8 shows in greater detail how the clinching anvil is constructed and mounted.

In view of the disclosure of the above-mentioned Letters Patent, only such parts of the general organization of the machine as it is necessary to consider for an understanding of the present invention will be hereinafter referred to. For pulling an upper successively in different locations along the edge of the shoe bottom as the shoe and last are presented by the operator in different positions, the machine is provided with a gripper comprising a pair of jaws 10 and 12, the jaw 10 being fast on a holder 14 having an upwardly extending tubular shank portion 16. The jaw 12 is supported on the holder 14 for swinging movements toward and from the jaw 10 to grip and release the upper, such movements being imparted thereto through a rod 18 slidingly mounted in the holder and in its shank portion 16. The gripper is moved heightwise of the last to pull the upper by an updraw lever 20 con-

55

connected to the shank portion 16 in a manner hereinafter described, this lever being operated by a power-driven cam on a cam shaft 22. As the gripper is moved downwardly by the lever 20 into position to grip the upper and is thereafter moved upwardly by the lever to pull the upper, the tubular shank portion 16 slides in a bearing provided in a guide block 24 connected as hereinafter described to a horizontal overdraw rod 26 by forward movement of which the gripper is swung forwardly toward the operator, in time relation to its upper-pulling movement heightwise of the last, to pull the marginal portion of the upper inwardly over the bottom of the last, and by rearward movement of which the gripper jaws are carried toward the edge of the shoe bottom preparatory to the gripping of the upper. For laying the marginal portion of the upper over and upon a sole on the last in time relation to each upper-pulling operation of the gripper the machine is further provided with an overlaying member 28 movable toward the shoe in a forwardly and downwardly inclined direction. This member in the machine herein shown comprises a nozzle from which a staple S (Figs. 6 and 7) is driven by a staple driver 30 to fasten the upper to the sole at the end of each overlaying operation. As herein illustrated, the staple is driven through the upper and through a lip on the sole, and its legs are clinched on the lip by an anvil 32 which engages the inner face of the lip and serves to position the shoe heightwise and laterally. As thus far described, the construction of the machine and the manner in which it operates, except as hereinafter noted, are substantially as disclosed in the previously mentioned Letters Patent.

To permit the gripper to be swung forwardly to pull the upper inwardly over the bottom of the last by forward movement of the overdraw rod 26 as above described, and also to permit it to be swung laterally, i. e., in directions lengthwise of the edge of the shoe bottom, for purposes of the present invention, it is connected to the updraw lever 20 by the means illustrated in Fig. 5. The shank portion 16 of the holder 14 is held at its upper end by a clamp 34 having an upwardly extending annular portion 36 from opposite sides of which project trunnions 38. One of the trunnions 38 is mounted in a bearing in a lug 40 which is part of a member 42, and the other trunnion is mounted in a bearing in a lug 44 provided with a pin 46 that projects through an opening in the member 42 and is threaded to receive a nut 48 which holds the lug 44 fast on the member 42. The member 42 has projecting therefrom a stem 50 which extends at right angles to the trunnions 38 and is mounted to turn in a bearing in the forward end of the updraw lever 20. A nut 52 on the stem 50 holds the member 42 in place on the updraw lever. It will thus be seen that the gripper may be swung forwardly about the axis of the stem 50 to pull the upper inwardly over the bottom of the last and may also be swung laterally about the axis of the aligned trunnions 38 to carry the gripper jaws in directions lengthwise of the edge of the shoe bottom.

Swinging movements of the gripper about both the above-mentioned axes are effected by movements of the guide block 24 which is connected to the overdraw rod 26 as will now be described. The overdraw rod has a vertically flattened front end portion 54 (Fig. 2), and projecting laterally of the gripper from one side of this

flattened portion of the overdraw rod is a short bar 56 which has a reduced threaded end 58 extending through the flattened portion of the overdraw rod and secured thereto by a nut 60. Mounted on the bar 56 to slide lengthwise thereof and also to turn thereon is a member 62 (Fig. 3) that is swiveled in the guide block 24, this member having a cylindrical portion 64 that engages peripherally arc-shaped upper and lower bearing faces formed in a recess in the guide block. At both sides of this cylindrical portion 64 the bar 56 projects through openings in the sides of the guide block 24 which are enough larger than the bar to permit the guide block to turn relatively to the bar as required in the lateral swinging movements of the gripper about the axis of the trunnions 38, as will be evident by reference to Fig. 1. The member 62 is further provided with upper and lower flanges 66 extending beyond the periphery of the cylindrical portion 64 and having arcuate faces engaging corresponding bearing faces formed on the block 24. The block 24 and the member 62 are held in assembled relation to each other by a plate 68 secured by cap screws 70 to the block 24 in overlapping relation to the flanges 66. It will thus be seen that the member 62 serves to connect the guide block 24 to the bar 56 in such manner that the gripper is swung in opposite directions by forward and rearward movements of the overdraw rod 26, the member 62 turning on the bar 56 in these movements.

The swinging of the gripper laterally, i. e., in directions lengthwise of the edge of the shoe bottom, for the purpose hereinbefore described is effected by rectilinear sliding movements of the member 62 along the bar 56. For this purpose the member 62 has projecting forwardly therefrom through an opening in the plate 68 two lugs 72 (Figs. 2 and 3) which have arcuate outer faces engaging a corresponding edge face of the plate 68 and vertically straight inner faces between which is located a roll 74 (Fig. 3). This roll is mounted on a crank pin carried by a forwardly and rearwardly extending shaft 76 which is rotatable in a bearing formed in a bracket 78 secured to the forward end of the overdraw rod 26 by screws 80 (Fig. 2). The roll 74 thus serves as an eccentric member in front of the gripper for swinging the gripper laterally by movement of the member 62. A reduced portion of the shaft 76 extends through a plate 82 secured to the bracket 78 and has on its forward end a collar 84 engaging the plate 82 to hold the shaft against lengthwise rearward movement, its forward movement being prevented by engagement of a flange 85 thereon with the bracket 78. Formed on the shaft 76 are gear teeth 86 which constitute a pinion integral with the shaft and engaged by the teeth of a gear sector 88 movable in a recess behind the plate 82. This gear sector is part of a member 90 rotatably mounted on a forwardly and rearwardly extending pin 92 which is secured to the bracket 78, the member 90 being forked so that portions thereof are supported on the pin 92 at opposite sides of an ear 94 on the bracket. Extending from the member 90 is a hand lever 96 by which the member may be turned by the operator at will to turn the shaft 76 and thereby swing the gripper in such manner as to carry its jaws in one direction or the other past the anvil 32 and the location of fastening insertion to position them for operation on the upper at either side of that location. A pin 98 projecting from the bracket 78 into a slot in the

member 90 serves to limit movements of the member in opposite directions and thus to determine the different positions of the gripper. It will be evident that the relation of the eccentric roll 74 to the member 62 is such as to permit the turning movements of this member on the bar 56 that necessarily occur in the forward and rearward movements of the overdraw rod 26.

Mechanism is further provided for maintaining the gripper yieldingly in either position to which it is swung by movement of the means above described, so that during the pull on the upper its jaws are positioned at a substantially fixed distance lengthwise of the edge of the shoe bottom from the location of fastening insertion. This mechanism comprises a member 100 which is fast on a rockshaft 102 mounted to turn in a bearing in the bracket 78, the member 100 having therein a plunger 104 which is pressed 20 downwardly by a spring 106 and has a rounded projection 108 seated in a corresponding recess in an arm 110 that is part of the member 90. A collar 112 (Fig. 3) on the rockshaft 102 holds the shaft against forward movement in its bearing. 25 By reference to Fig. 2 it will be evident that, as the parts are there positioned, the plunger 104 by its action on the arm 110 serves to retain the member 90 and the gripper yieldingly in the positions indicated, since the force exerted on 30 the arm 110 by the plunger 104 is along a line at the right-hand side of the axis of movement of the member 90. When the member 90 is turned to move the gripper to the other position determined by the pin 98, the arm 110 by its 35 action on the plunger 104 causes the member 100 to turn with the shaft 102 to a position in which the force of the plunger is directed along a line at the left-hand side of the axis of the member 90 and therefore serves to maintain this member 40 yieldingly in that position. Accordingly the arm 110 and the spring-pressed plunger 104 comprise toggle-like members which serve to maintain the gripper yieldingly in either of the positions to which it is swung by the hand lever 96.

45 It is important that in each cycle of the machine the gripper jaws shall be so positioned as to operate either at one side or at the other side of the anvil 32, since if they should occupy an intermediate position they would strike the anvil 50 in their rearward movement to grip the upper and parts of the machine would be broken. Mechanism is accordingly further provided for insuring against such damage to the machine. For this purpose one of the arms of the previously 55 mentioned forked portion of the member 90 has thereon an upwardly extending lug 114 (Fig. 2) to which is fastened a member 116 having a V-shaped upper edge portion. Arranged to cooperate with this member is a slide 118 having a V-shaped lower edge portion, this slide being vertically movable in a guideway formed in an upward extension of the bracket 78. Fastened to the slide 118 is a member 128 connected by a link 122 to a lever 124 (Fig. 1) which is mounted for 60 swinging movements in a vertical plane and extends rearwardly to a position over the cam shaft 22. At its rear end the lever 124 carries a screw 126 which rests on the upper end of a slide 128 (Fig. 4) guided for vertical movements in the 65 frame of the machine. The slide 128 at its lower end carries a roll 130 engaged by a cam disk 132 on the cam shaft 22. This cam disk has therein a depression 134 (Fig. 1) in which the roll 130 lies when the parts of the machine are in 70 their starting positions. A spring 136 connected

to the rear end of the lever 124 tends to pull this end of the lever downwardly and thus holds the roll 130 at all times in engagement with the cam disk 132. Immediately upon the starting of the machine the cam disk serves to raise the slide 128 and thereby to swing the lever 124 in the direction to move the slide 118 (Fig. 2) downwardly along its guideway. If, therefore, the gripper should be accidentally positioned at this time between the limits of its opposite lateral swing- 10 movements, so that its jaws might strike the anvil 32, the lower V-shaped portion of the slide 118 engages the corresponding upper portion of the member 116 at one side or the other of the latter and thereby imparts to the member 90 such 15 movement that the gripper jaws are carried to one or the other of their normal starting positions before they receive their rearward movements to seize the upper.

In order to permit the gripper jaws to be swung 20 laterally past the clinching anvil as above described, the anvil 32 herein shown is constructed and mounted somewhat differently than in earlier machines of the illustrated type. The anvil 32 is formed from a plate of spring steel and is ad- 25 justably secured to a rod 138 (Figs. 1 and 8) which is clamped in a split bearing formed in a bracket 140, this being the bracket on which the anvil has been supported heretofore. The anvil is mounted in an opening formed in one side of 30 the rod 138 and is provided with beveled edges one of which extends into a corresponding recess in the rod and the other of which is engaged by a clamp member 142 held by a washer 144 and a screw 146 on the end of the rod. It will 35 thus be evident that the anvil may be adjusted upwardly and downwardly after loosening the screw 146 and that it may also be adjusted to position its lower end nearer to or farther from the staple-guiding member 28 by turning the rod 40 138 in its bearing in the bracket 140. Since the anvil is made of spring steel, it may yield to accommodate itself to different thicknesses of 45 shoe materials clamped between it and the member 28. By reference to Fig. 1 it will be evident 50 that the anvil is so formed and mounted as to afford clearance for the gripper jaws as the jaws are swung past it in one direction or the other when the parts of the machine are in their starting positions.

Figs. 6 and 7 illustrate how the machine, constructed as described, may be used in lasting the opposite sides of a shoe. In Fig. 6 the gripper jaws are so positioned as to operate at the right-hand side of the location of fastening insertion, and accordingly the operator moves the shoe from right to left to present it successively in different positions for lasting, the lasting operation progressing as illustrated from the toe portion of the shoe toward the heel portion. To permit the lasting operation to progress from the toe portion toward the heel portion also in lasting the other side of the shoe, the gripper jaws in Fig. 7 are positioned to operate at the left-hand side of the location of fastening insertion so that the shoe may be moved from left to right. It will be evident that by the mechanism described the operator is enabled to effect a practically instantaneous shifting of the gripper from one position to the other to accomplish the objects in view. If the operator desires to use the machine in the same manner as machines of the illustrated type have been used heretofore, he may leave the gripper jaws positioned as illustrated in Fig. 7 and oper- 75

ate on both sides of the shoe with the jaws in that position.

The invention having thus been described, what is claimed as new and what it is desired to secure by Letters Patent of the United States is:

1. In a lasting machine, a gripper having jaws for gripping and pulling an upper successively in different locations along the edge of the bottom of a shoe, and means for fastening the upper after each upper-pulling operation, said gripper and fastening means being relatively movable at the will of the operator to dispose the upper-engaging portions of the gripper jaws for operation on the upper in a location spaced during the pull a substantially fixed distance lengthwise of the edge of the shoe bottom from the location where said fastening means operates on the shoe either at one side or at the other side of that location selectively.

2. In a lasting machine, a gripper having jaws for gripping and pulling an upper successively in different locations along the edge of the bottom of a shoe, means for inserting a fastening to fasten the upper after each upper-pulling operation, and mechanism for shifting the gripper at the will of the operator to position the upper-engaging portions of its jaws for operation on the upper in a location spaced during the pull a substantially fixed distance lengthwise of the edge of the shoe bottom from the location where said fastening-inserting means operates on the shoe either at one side or at the other side of that location selectively.

3. In a lasting machine, a gripper having jaws for gripping and pulling an upper successively in different locations along the edge of the bottom of a shoe, means for inserting a fastening to fasten the upper after each upper-pulling operation, said gripper being shiftable at the will of the operator to carry the upper-engaging portions of its jaws in directions lengthwise of the edge of the shoe bottom past the location of fastening insertion and thus to position the jaws for operation on the upper at either side of that location selectively, and means for maintaining said jaws at a substantially fixed distance lengthwise of the edge of the shoe bottom from said location of fastening insertion during the pull of the gripper on the upper.

4. In a lasting machine, a gripper having jaws for gripping and pulling an upper successively in different locations along the edge of the bottom of a shoe on a last, and overlaying means for laying the marginal portion of the upper inwardly over a sole on the last in time relation to each upper-pulling operation, said gripper being shiftable at the will of the operator to position the upper-engaging portions of its jaws for operation on the upper in a location spaced during the pull a substantially fixed distance lengthwise of the edge of the shoe bottom from the location where said overlaying means operates on the upper either at one side or at the other side of that location selectively.

5. In a lasting machine, a gripper having jaws for gripping and pulling an upper successively in different locations along the edge of the bottom of a shoe on a last, overlaying means for laying the marginal portion of the upper inwardly over a sole on the last in time relation to each upper-pulling operation, said gripper being mounted for swinging movements to carry the upper-engaging portions of its jaws in directions lengthwise of the edge of the shoe bottom past

the location where said overlaying means operates on the upper and thus to position the jaws for operation at either side of that location selectively, and mechanism movable by the operator to effect such swinging movements of the gripper and constructed to hold the gripper against swinging movement lengthwise of the edge of the shoe bottom during its pull on the upper. 5

6. In a lasting machine, a gripper having jaws for gripping and pulling an upper successively in different locations along the edge of the bottom of a shoe, means for driving a fastening through the upper and through a lip on a sole to fasten the upper after each upper-pulling operation, and an anvil for clinching each fastening, said gripper being shiftable to position the upper-engaging portions of its jaws for operation on the upper in a location spaced lengthwise of the edge of the shoe bottom from said anvil either at one side or at the other side of the anvil selectively. 10 15 20

7. In a lasting machine, a gripper having jaws for gripping and pulling an upper successively in different locations along the edge of the bottom of a shoe, means for driving a fastening through the upper and through a lip on a sole to fasten the upper after each upper-pulling operation, and an anvil for engaging said lip and for clinching each fastening on the lip, said gripper being shiftable to carry the upper-engaging portions 30 35 of its jaws past the anvil in directions lengthwise of the edge of the shoe bottom for operation on the upper either at one side or at the other side of the anvil, and said anvil being constructed and arranged to permit the jaws thus to pass it when the parts of the machine are in their starting positions. 30

8. In a lasting machine, a gripper having jaws for gripping and pulling an upper successively in different locations along the edge of the bottom of a shoe on a last, means for fastening the upper to a sole on the last after each upper-pulling operation, said gripper being mounted for swinging movements to carry the upper-engaging portions of its jaws in directions lengthwise of the edge of the shoe bottom into position for operation of the upper in a location spaced lengthwise of the edge of the shoe bottom from the location where said fastening means operates on the shoe either at one side or at the other 40 45 50 side of that location selectively, and mechanism movable by the operator to effect such swinging movements of the gripper and constructed to hold the gripper against swinging movement lengthwise of the edge of the shoe bottom during its pull on the upper. 55

9. In a lasting machine, a gripper having jaws for gripping and pulling an upper successively in different locations along the edge of the bottom of a shoe, means for fastening the upper after each upper-pulling operation, said gripper being movable at the will of the operator to position the upper-engaging portions of its jaws for operation on the upper in a location spaced lengthwise of the edge of the shoe bottom from the location where said fastening means operates on the shoe either at one side or at the other side of that location selectively, and automatic means for insuring the proper positioning of the gripper to operate thus at one side or the other of 60 65 70 the location where the fastening means operates.

10. In a lasting machine, a gripper having jaws for gripping and pulling an upper successively in different locations along the edge of the bottom of a shoe, said gripper being mounted for 75

5 swinging movements to carry its jaws laterally to different selected starting positions, an eccentric member for thus swinging the gripper, a pinion mounted to turn with said eccentric member, and a member having teeth engaging said pinion and movable by the operator to turn the pinion.

10 11. In a lasting machine, a gripper having jaws for gripping and pulling an upper successively in different locations along the edge of the bottom of a shoe, said gripper being mounted for upward movement to pull the upper and also for lateral movements to carry its jaws to different selected starting positions, a shaft located in front 15 of the gripper and movable about a forwardly and rearwardly extending axis to impart said lateral movements to the gripper, a connection between said shaft and the gripper in a location substantially opposite the rear end of the shaft, 20 and means movable by the operator to turn said shaft.

25 12. In a lasting machine, a gripper having jaws for gripping and pulling an upper successively in different locations along the edge of the bottom of a shoe, said gripper being mounted for upward movement to pull the upper and also for lateral movements to carry its jaws to different selected starting positions, a member rotatable about a forwardly and rearwardly extending axis to im- 30 part said lateral movements to the gripper, a pinion rotatable with said member, and another member movable by the operator about a forwardly and rearwardly extending axis and having teeth engaging said pinion for turning it.

35 13. In a lasting machine, a gripper having jaws for gripping and pulling an upper successively in different locations along the edge of the bottom of a shoe, said gripper being mounted for swinging movements to carry its jaws laterally to different selected starting positions, a guide for the gripper mounted to swing with it, a member swiveled in said guide and mounted to slide in directions laterally of the gripper, and means for thus sliding said member and thereby swing- 40 ing the gripper.

45 14. In a lasting machine, a gripper having jaws for gripping and pulling an upper successively in different locations along the edge of the bottom of a shoe on a last, said gripper being mounted for lateral swinging movements to carry its jaws to different selected starting positions and also for forward swinging movement to pull the upper inwardly over the bottom of the last, an over- 50 draw rod movable thus to swing the gripper forwardly, and mechanism comprising intermeshing toothed members carried by said overdraw rod for imparting to the gripper its lateral swing- 55 ing movements.

60 15. In a lasting machine, a gripper having jaws for gripping and pulling an upper successively in different locations along the edge of the bottom of a shoe on a last, said gripper being mounted for lateral swinging movements to carry its jaws to different selected starting positions and also for forward swinging movement to pull the upper inwardly over the bottom of the last, an over- 65 draw rod movable thus to swing the gripper forwardly, and mechanism supported as a whole by said overdraw rod for imparting to the gripper its lateral swinging movements and for retaining it in the selected starting position.

70 75 16. In a lasting machine, a gripper having jaws for gripping and pulling an upper successively in different locations along the edge of the bottom of a shoe on a last, said gripper being mounted

for lateral swinging movements to carry its jaws to different selected starting positions and also for forward swinging movement to pull the upper inwardly over the bottom of the last, an overdraw rod movable thus to swing the gripper forwardly, 5 a bar carried by said overdraw rod and extending in directions laterally of the gripper, connections between said bar and the gripper comprising a member mounted to turn on the bar in the forward swinging movement of the gripper and also slidable along the bar to impart to the gripper its lateral swinging movements, and means for thus sliding said member to swing the gripper laterally.

10 15 17. In a lasting machine, a gripper having jaws for gripping and pulling an upper successively in different locations along the edge of the bottom of a shoe on a last, said gripper being mounted for lateral swinging movements to carry its jaws to different selected starting positions and also for forward swinging movement to pull the upper inwardly over the bottom of the last, an overdraw rod movable thus to swing the gripper forwardly, 15 a bar carried by said overdraw rod and extending in directions laterally of the gripper, connections between said bar and the gripper comprising a member mounted to turn on the bar in the forward swinging movement of the gripper and also slidable along the bar to impart to the gripper its lateral swinging movements, and means for thus sliding said member to swing the gripper laterally.

20 25 30 35 40 45 18. In a lasting machine, a gripper having jaws for gripping and pulling an upper successively in different locations along the edge of the bottom of a shoe on a last, said gripper being mounted for lateral swinging movements to carry its jaws to different selected starting positions and also for forward swinging movement to pull the upper inwardly over the bottom of the last, an overdraw rod movable thus to swing the gripper forwardly, a bar carried by said overdraw rod and extending in directions laterally of the gripper, connections between said bar and the gripper comprising a member mounted to turn on the bar in the forward swinging movement of the gripper and also slid- 50 able along the bar to impart to the gripper its lateral swinging movements, and mechanism comprising a rotatable eccentric member carried by said overdraw rod for moving said slid- 55 able member along the bar to swing the gripper laterally, the different members being so constructed and arranged as to permit the slid-able member to turn on the bar relatively to the eccentric member.

60 65 19. In a lasting machine, a gripper having jaws for gripping and pulling an upper successively in different locations along the edge of the bottom of a shoe, said gripper being mounted for movements in opposite directions to carry its jaws laterally to different selected starting positions, and a pair of toggle-like members mounted to swing as the gripper is moved to its different positions and arranged to maintain the gripper yield- 70 ingly in either of said positions.

75 20. In a lasting machine, a gripper having jaws for gripping and pulling an upper successively in different locations along the edge of the bottom of a shoe, said gripper being mounted for movements in opposite directions to carry its jaws laterally to different selected starting positions, and a pair of toggle-like members mounted to swing as the gripper is moved to its different positions, one of said members comprising a spring- controlled plunger arranged to cooperate with the 75

other member to maintain the gripper yieldingly in either of said positions.

21. In a power-operated lasting machine, a gripper having upper-gripping jaws and operatively movable to pull an upper successively in different locations along the edge of the bottom of a shoe, said gripper being mounted for movements in opposite directions at the will of the operator to carry its jaws laterally to different selected starting positions, and means movable in automatically determined time relation to the operative movement of the gripper after the starting of the power operation of the machine to insure that the jaws will occupy one or the other of said starting positions.

22. In a lasting machine, a gripper having

upper-gripping jaws and operatively movable to pull an upper successively in different locations along the edge of the bottom of a shoe, said gripper being mounted for movements in opposite directions at the will of the operator to carry its jaws laterally to different selected starting positions, mechanism movable by the operator to impart to the jaws such lateral movements, and a device movable in automatically determined time relation to the operative movement of the gripper and arranged to act on said mechanism to force the jaws toward one or the other of said starting positions if they are accidentally displaced. 5 10 15

ISABELLE W. GODDU, 15
Executrix of the Will of George Goddu, Deceased.
